UNITED STATES PATENT OFFICE.

JOSEPH W. PHINNEY, OF MEDFORD, MASSACHUSETTS.

DESIGN FOR A FONT OF TYPE.

SPECIFICATION forming part of Design No. 29,773, dated December 6, 1898.

Application filed August 22, 1898. Serial No. 689,254. Term of patent 7 years.

To all whom it may concern:

Be it known that I, JOSEPH W. PHINNEY, of Medford, in the county of Middlesex and State of Massachusetts, have invented and produced a new and original Design for a Font of Type, of which the following is a specification.

This design comprises capital letters, combinations of the capital W with a small h and small i, and lower-case letters, combinations of tt and th, and also Arabic numerals, character &, the dollar and pound-sterling marks, and punctuation-marks.

The general characteristic of the font is a script, the stems of the letters being heavy in comparison with the serifs and other fine lines. The letters are quite open, and the fine lines of the capitals, with the exception of the D, H, O, Q, and U, terminate in a pronounced dot, which in some cases, where the fine line connecting the dot with the stem is short, renders the fine line very inconspicuous by contrast. The capitals B and G have, in addition to the terminal dot referred to, a central dot forming a portion of the upper part of the letter, and the capital R is a similar dot. The curves, especially in the capitals A, C, F, G, K, L, M, T, V, and W, are somewhat exaggerated, and the letter H is com-

posed of two wedge-shaped stems connected 30 by a slight curve.

The small letters are chiefly characterized by the fact that the stem is quite broad in proportion to the fine line, so that the fine line is quite indistinct by comparison. The 35 upper terminal of the c and both terminals of the f and the lower parts of the g, j, and y and both terminals of the z, as well as the upper terminal of the interrogation-point, are dots connected to the stem of the character 40 by a line very fine in contrast with the line of the stem. The stems of the small letters b, d, h, k, l, and t project considerably above the shorter letters, so that these letters are a little more than twice the height of the shorter 45 letters, and in the same way the downward projection of the letters d, j, p, q, and y is also about twice the length of the height of the smaller letters.

What I claim is—

The design for a font of type herein shown and described.

In testimony whereof I have hereunto set my name this 10th day of August, 1898.

JOSEPH W. PHINNEY.
